UNITED STATES PATENT OFFICE.

JOHN I. MARTIN, OF AKRON, OHIO.

DESIGN FOR A TIRE TREAD.

Application filed March 21, 1921. Serial No. 454,308. Term of patent 14 years.

To all whom it may concern:

Be it known that I, JOHN I. MARTIN, a citizen of the United States, residing at Akron, in the county of Summit, State of Ohio, have invented a new, original, and ornamental Design for Tire Treads, of which the following is a specification, reference being had to the corresponding drawings, forming a part thereof.

In the drawings, Fig. 1 is a side elevation of the tire tread.

Fig. 2 is a plan view.

Fig. 3 is a cross section on the line 3—3 of Fig. 4.

Fig. 4 is a developed plan view.

I claim:

The ornamental design for a tire tread as shown.

JOHN I. MARTIN.
